FITTING FOR A LUGGAGE CASE OR SIMILAR ARTICLE

David Levine, New York, N. Y., assignor to Crest Lock Co., Inc., New York, N. Y., a corporation of New York

Application October 21, 1948, Serial No. 149,221

Term of patent 14 years

(CL. D87—2)

To all whom it may concern:

Be it known that I, David Levine, a citizen of the United States, residing at the Borough of Manhattan, in the county of New York and State of New York, have invented a new, original, and ornamental Design for a Fitting for a Luggage Case or Similar Article, of which the following is a specification, reference being had to the accompanying drawing, forming part thereof.

In the drawing:

Fig. 1 is a front perspective view of a fitting for a luggage case or similar article showing my new design;

Figs. 2 and 3 are left and right hand side elevational views, respectively, of the fitting as shown in Fig. 1; and

Fig. 4 is a rear elevational view of the fitting on a reduced scale.

I claim:

The ornamental design for a fitting for a luggage case or similar article, as shown and described.

DAVID LEVINE.
